SIGNORS TO WORLEY & CO., OF LOS ANGELES, CALIFORNIA, A CORPORATION OF
CALIFORNIA

LATCHING MECHANISM FOR LOCKERS

Application filed May 19, 1924. Serial No. 714,323

This invention has to do generally with lockers or cabinets wherein hinged doors are provided with latching mechanisms for holding them closed, and is more particularly concerned with a novel type of latching mechanism together with means for locking the mechanism against movement.

The invention is particularly applicable to lockers of the sheet metal type, such as are used in schools or factories for the reception and storage of clothing, each locker being of a size to receive the clothing or wraps of but one or two individuals. In order properly to fulfill their function, such lockers must have door openings of considerable vertical extent, and yet the latching and locking mechanism on the relatively long, narrow doors must be of relative light construction but of a character to resist tampering. Consequently it is customary to latch such doors at a plurality of points along the door jamb and to provide an actuating bar common to all of the latches.

It is among the objects of our invention to provide a door latching and locking mechanism which especially well meets the requirement noted above, mechanism that is durable, simple of construction, easily installed without unduly mutilating the locker door, comparatively light, and capable of effectively resisting all but the most strenuous attempts to force the door.

Preferably, the latches are gravity actuated and are adapted to engage their keepers automatically during door closing movement, though our invention, in its broader aspects, is not limited to mechanisms having these particular characteristics.

As differentiated from the usual type of latching mechanism (wherein a plurality of latches are rigidly mounted on a common latch bar, or where a sliding latch bar is adapted to engage a plurality of stationary latch elements) we have independently and pivotally mounted the several latches on the door. A vertically slidable latch bar has

toothed connection with the several latches whereby latch bar reciprocation, accomplished by movement of a handle directly connected to the bar and movable over the outer face of the door, imparts pivotal movement to the latches and thereby releases them from engagement with keepers which are provided on the stationary part of the locker structure.

The pivotal mountings of the latches and the connections between the latches and latch bar are so relatively arranged that the latches are adapted to rotate beneath and engage their keepers from below, and gravity, acting on the bar, serves yieldingly to retain the latches in latching position; the latches being disengaged from their keepers by lifting the bar through the medium of its handle. Thus, we accomplish latch disengagement by imparting a natural lifting movement to the handle, and yet no reversing mechanism need be provided between handle and latches. This construction reduces the number of working parts to a minimum, and due to the independent mounting of each latch and the relatively loose connection between the latches and their common bar, strains imposed on one latch are not transferred to another, and prying action directed against the bar in no way effects the locking engagement of the latches. Since the latches are exposed only to minor strains and to no accumulated strains, they may be of comparatively light construction, an obvious advantage from the standpoint of the manufacturer and purchaser.

We have also devised a novel padlock attachment which has many points of superiority, but this, together with other features of novelty and objects of the invention, may be discussed to better advantage in the following detailed description, reference being had to the accompanying drawings in which:

Fig. 1 is a front elevation of a locker equipped with our latching mechanism;

Fig. 2 is a detached perspective view of a

door equipped with our latches and as viewed from the inside thereof;

Fig. 3 is a fragmentary perspective view of the inside of the door with the latch bar removed;

Fig. 4 is a fragmentary perspective view of a door frame member with an associated keeper;

Fig. 5 is a fragmentary perspective showing the mechanism of Figs. 3 and 4 in assembled and coacting relation together with a bar for moving the latches; a lock being shown in dotted lines in order to expose more fully the connection between the latch bar and the handle;

Fig. 6 is an elevation of the door and door frame members with one of the latches in engagement with its keeper, the mechanism being shown as viewed from the inside of the locker, and one of the side walls or plates of the locker being shown in section;

Fig. 7 is an enlarged section on line 7-7 of Fig. 1; and

Fig. 8 is a horizontal section on line 8-8 of Fig. 7.

At the outset, we wish to make the reservation that while we have illustrated and will describe the locker as having an angle iron door frame, and the door as being provided with an internal marginal flange to which the latches are pivoted, these features are not necessary to the invention in its broader aspects, and their illustration and description are not to be construed as limiting the invention.

First referring to Fig. 1 the door frame of the locker is made up of horizontal angle iron 10 and vertical angle irons 11 and 12, the side and top plates P of the locker being joined to the frame in any suitable manner. Door 13, in its preferred form, is made up of sheet metal plate 14 hinged to frame angle 12 at 15 and having an inturned marginal flange 16 (Fig. 2). That portion of the flange which outlines the free edge of the door is designated by the individual numeral 17 (Fig. 3).

Vertically spaced along and secured to frame angle 11, which lies adjacent flange 17 when the door is closed, are the several keepers 18. While the exact number and form of keepers is not important to this invention, we have illustrated three of them, each consisting of a foot piece 19 fastened to the forward leg of iron 11, a portion 20 which extends substantially parallel to flange 17 when the door is closed, and a cross bar 21 extending at substantially right angles with portion 20 and lying across the inner edge of flange 17 when the door is closed. The cross-bars of one or all the keepers may have notches 22 to provide opposed stop shoulders 23 and 24 along the lower edges thereof, these stop shoulders serving to prevent the door from being forced by inserting

a prying tool between the door frame and latch.

Pivoted at 25 along flange 17 and in alignment with keepers 18, are the oscillatory latches 26. If desired the latches may be horizontally spaced from the flange by washer 27 (Fig. 6). The latches being typical, we will describe but one in detail. At one side of pivot 25 is provided a hook 28 having a bevel or cam nose 29 and adapted to engage beneath and behind an associated keeper bar 21. At the other side of pivot 25 is provided a projection or tooth 30 which extends at substantially right angles with the body of the latch.

A latch bar 31 is vertically slidable along flange 17, being guided and limited in its movement by headed studs 32 which are anchored on the flange and extend through suitable bar slots 33. Preferably, the major portion of the bar bears on the inner face of flange 17, and the bar is offset at 31^a so as to overlie and clear latches 26. The bar offsets have notches 34 along their edges, each notch being adapted to receive the projection 30 of an aligned latch. The horizontal extent of a given notch is such that requisite lost motion between bar and latch may occur during their relative movement. It will be seen that we have provided a pin and slot connection (or it may also be properly called a "toothed connection") between bar and latches, and that reciprocatory movement of the bar imparts oscillatory movement to the latches. Of course, it lies within the scope of our broader claims to vary the connection over the exact structure shown. For instance, the teeth and slots might be reversed as regards the element on which they are provided; tooth 30 and bar 31 might extend in the vertical plane and to the rear of the latch, proper; or a series of meshing teeth might be provided on the latch and bar.

With bar 31 at the limit of its down movement as established by studs 32, latches 26 are in "latching position" and are in engagement with keepers 18 when the door is closed. In order to lift bar 31 and thereby rotate latches 26 in a clockwise direction, as viewed in Fig. 5, in order to release hooks 28 from keepers 18, we provide a handle 35 which is vertically movable over the outer face of door 13 and is connected to bar 31 by horizontal arms 37, one or more in number. Preferably, arms 37 have enlargements or bosses 38 intermediate their ends, which bosses are adapted to bear against the door face, and the inner portions 37^a of the arms extend through door slots 39 and 40. For the time being, we will disregard the peculiar characteristics of the slot formation and will merely state that the slots are of sufficient vertical extent to admit of necessary handle movement. While we prefer to establish the limit of latch bar movement (which limit, in turn, determines the

extreme positions of the latches) by studs 32 and slots 33, it is obvious that we may proportion slots 39 so they, with arms 37^a may serve to establish the limit of latch bar movement.

After the operator lifts handle 35 to rotate the latches in a clockwise direction, as viewed in Fig. 5, out of engagement with their keepers, a pull on the handle serves to swing the door open, and when the handle is subsequently released, bar 31 gravitates back to normal position, thereby rotating the latches in a counter-clockwise direction back to latching position. When the door is subsequently swung shut, the handle need not be lifted to reengage the latches and keepers, for cam noses 29 ride beneath bars 21, rotating the latches in a clockwise direction and coincidentally lifting the bar with its handle, and as the door closes and as noses 29 clear the keeper bars, bar 31 gravitates and causes a re-engagement of the latches and their keepers.

We have illustrated two locking devices for the latch mechanism, either or both of which may be used in connection with a given locker.

In Figs. 5 and 6 we have shown a lock 41, of either the key-actuated or combination type, secured to door plate 14 at 42 and having a usual nose projecting through the outer face of the door through aperture 44 (Fig. 1). The lock bolt 45 is adapted to be shot over one of the handle arms 37^a to prevent the latch bar from being lifted and hence preventing disengaging rotation of the latches.

We have provided a novel padlock attachment, best illustrated in Figs. 7 and 8. Aperture 40 through which the lower arm 37^a extends, is comparatively wide and is formed by first cutting plate 14 and then bending or pressing the lip 46, which is defined by the cut, outwardly from the face of the door so it forms a stationary lock element or projection. Preferably, the lip is cut away so it stops considerably short of the bottom of the aperture as clearly shown in Fig. 7. Boss 38 on arm 37 has a vertically extending way 47 which receives lip 46 and normally allows uninterrupted movement of the handle over the lip. In effect, therefore, boss 38 is a yoke which straddles the stationary lock element 46. The arms of the yoke have registering eyes 48 which lie just beneath lip 46 when the handle is in lowermost position, and the eyes are adapted to receive the shackle or bolt 49 of padlock 50. It is obvious that the shackle, in its engagement with the lower edge of the lip, will prevent upward movement of handle 35 and thereby prevent disengagement of the latches from their keepers. Boss 38 protects lip 46 against tampering, and since way 47 is of considerable length, the lip is enclosed throughout all stages of handle movement.

In the event it is desired to lock the latch

mechanism in such a position that the latches may not be brought into engagement with their keepers, for instance, after a locker renter has given up possession of a particular locker, the handle may be lifted and the padlock shackle inserted above lip 46 (assuming apertures 39 and 40 are of sufficient extent to allow this handle movement) to prevent subsequent lowering of the handle. With lock 41 in use, the same effect may be gained by shooting bolt 45 beneath arm 37^a after the handle is raised.

It will be understood that various changes in design, arrangement and structure may be made without departing from the spirit and scope of our invention and therefore we wish to reserve to ourselves all changes which lie within the scope of our broader claims.

Having described a preferred form of our invention, we claim:

1. A locker having a door hinged thereto, a plurality of keepers secured to the locker adjacent the door, latches pivotally mounted on the door and adapted to engage the keepers, a latch bar longitudinally slidable upon the door and having toothed connection with the latches whereby longitudinal movement of the bar imparts pivotal movement to the latches, a stationary locking element on the outer face of the door and formed by cutting the door and pressing outwardly that portion of the door which is defined by the cut, a handle movable over the outside of the door and having an arm extending through the aperture which is left in the door by the outward pressing of the locking element, said arm being connected to said latch bar, and releasable means adapted to coact with the handle and locking element for preventing relative movement therebetween.

2. In a locker having a door frame and a door hinged at one edge thereto, the free edge of the door being turned inwardly to form a vertically extending and substantially right angle flange therealong, said flange extending horizontally into the interior of the locker, a plurality of keepers secured to the door frame adjacent the flange, latches pivotally mounted on the flange and adapted to engage the keepers, the latches being further adapted to oscillate in a plane substantially parallel to the flange plane, projections on and extending at substantially right angles to the latches, a latch bar vertically slidable upon the flange and having offset portions overlying the latches, said offset portions being provided with notches adapted to receive said latch projections, the notch and projection connections between bar and latches being adapted to translate vertical movement of the bar into pivotal movement of the latches, and a movable handle on the outside of the door and operatively connected to the latch bar.

3. In a locker, the combination of a sheet

- metal door, a movable latching element on the inside of the door, a handle movable over the outer face of the door and operatively connected to the latching element, a locking element on the outer face of the door and formed by cutting the door and pressing outwardly that portion of the door which is defined by the cut, and releasable means adapted to coact with the handle and locking element to prevent relative movement therebetween.
4. In a locker, the combination of a sheet metal door, a movable latching element on the inside of the door, a handle movable over the outer face of the door and operatively connected to the latching element, a locking element on the outer face of the door and formed by cutting the door and pressing outwardly that portion of the door which is defined by the cut, said locking element being so positioned that it is traversed by the handle during movement thereof, and releasable means adapted to coact with the handle and locking element to prevent relative movement therebetween.
5. In a locker, the combination of a sheet metal door, a locking element on the door formed by cutting the door and pressing outwardly that portion of the door which is defined by the cut, a movable latching element on the inside of the door, a handle movable over the outer face of the door, an arm on the handle and extending through the aperture which is left in the door by the outward pressing of the locking element, said arm being adapted to operatively connect the handle and latching element, and releasable means adapted to coact with the handle and locking element for preventing relative movement therebetween.
6. In a locker, the combination of a sheet metal door, a movable latching element on the inside of the door, a handle movable over the outer face of the door and operatively connected to the latching element, a stationary lock member projecting from the outer face of the door, said member being formed by cutting the door and pressing outwardly that portion of the door which is defined by the cut, a yoke on the handle adapted to straddle and traverse the lock member during movement of the handle, and releasable means adapted to coact with the yoke and member for preventing relative movement therebetween.
7. In a locker having a door frame and a door hinged at one edge thereto, the free edge of the door having a vertically extending and substantially right angle flange therealong, said flange extending horizontally into the interior of the locker, a plurality of keepers secured to the door frame adjacent the flange, latches pivotally mounted on the flange and adapted to oscillate in a plane substantially parallel to the flange plane into and out of engagement with the keepers, a latch bar

mounted on the flange for vertical sliding movement therealong, operative connections between the bar and latches whereby vertical movement of the bar imparts pivotal movement to the latches, and a handle on the outside of the door for moving the latch bar vertically.

In witness that we claim the foregoing we have hereunto subscribed our names this 10th day of May, 1924.

JOHN WORLEY, Jr.
ELMER L. VREELAND.
